UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

PULLING-OVER APPARATUS.

1,176,022.

Specification of Letters Patent. Patented Mar. 21, 1916.

Application filed June 9, 1913. Serial No. 772,602.

To all whom it may concern:

Be it known that I, ARTHUR BATES, a subject of the King of England, residing at Leicester, Leicestershire, England, have invented certain Improvements in Pulling-Over Apparatus, of which the following description, in connection with the accompanying drawings, is a specification, like reference characters on the drawings indicating like parts in the several figures.

This invention relates to pulling-over apparatus and its object is to provide a simple, light and easily operated machine which may be mounted on either a bench or a floor base and is adapted for use on work where the requirements are not high for the operation of preparing shoes for lasting, as for example in *weldtschoen* or stitchdown work as herein illustrated or for other cheap work.

One feature of this invention consists in a novel combination with toe and side grippers and a tread rest of an actuator which is operatively connected with the grippers in such a manner that its actuation will cause the toe gripper to seize the upper and then move forward longitudinally of the last before the side grippers seize the upper. Preferably the actuator is operated manually so that the upper may be stretched longitudinally to the satisfaction of the operator before it is seized by the side grippers. Preferably the actuator that closes the toe gripper will move the tread rest away from the toe gripper.

Another feature of this invention consists in the combination with the side grippers and a sole rest, of connected operating mechanism organized to cause the grippers to pull the upper and to cause the rest to move the last backwardly within the upper while the side grippers are pulling the upper.

In its general organization as well as in various particular arrangements for performing its intended functions and in the construction and combination of parts, all of which will appear from the following description of a preferred embodiment of it, are to be found other novel features of this invention which will be pointed out in the claims at the end of the description.

Figure 1 of the accompanying drawings is a side elevation of the machine partly in section, showing the column and head mounted on a floor base; Fig. 2 is a front elevation of the same, also partly in sec-

tion; Fig. 3 is a detail of a modification in the toe gripper mechanism; Fig. 4 is a side elevation partly in section of a simpler construction arranged as a bench machine; Fig. 5 is a front view of the same in section, and Fig. 6 is a plan.

The base of the machine adjustably supports, or may be formed integral with, a column 2 through which is vertically movable an operating plunger 4. A horizontal guide member 5 is mounted in the ends of front and rear forks which rise from the column. The rear fork pivotally supports an upright arm 6 in which a binding screw 8 holds a lug 10 in vertical adjustment. A sole rest carrier 12 is pivoted to the upper end of the lug 10 as is also the sole rest plate 14 the front end of which is upturned as at 15. The front end of the sole rest plate rests upon the upper end of an adjusting screw 16 mounted in the sole rest carrier. The front end of the sole rest carrier is pivotally supported on the upper ends of levers 18 which are fulcrumed at 19 to the guide member 5, the lower ends being connected by forwardly extending links 20 to the front end of a horizontal bar 22 which extends longitudinally of the machine and is mounted in the head of the plunger 4. Depression of the plunger operates through the links 20 to rock the levers 18 as indicated by dotted lines, Fig. 1, to move the sole rest rearwardly in the machine.

The bar 22 has a collar 24 between upright ears of which is secured by a pin and slot connection a rod 25 to the upper end of which is pivoted the pulling lever 26 of the toe gripper, said lever having a rearwardly bent upper end which forms the upper jaw of the toe gripper. A spring 28 holds the toe gripper rocked toward the sole rest and against an adjustable stop 29 projecting from the sole rest carrier 12. The spring 28 also holds the gripper in its elevated position limited by a collar 27 carried on the rod 25 and butting against the guide member 5.

The gripping lever 30 on the rear end of which is formed the lower toe gripper jaw is pivoted to the pulling lever 26 at 32 and is connected by a link 34 to the bar 22 on the head of the plunger 4. This connection is made by a reduced portion of the link 34 which is extended through a pivot block in the end of bar 22 and encircled below said

pivot block by a spring 35 which forms a yielding operative connection between the plunger 4 and the toe gripper, the tension of the spring 35 being made variable by an adjusting nut 36.

Depression of the plunger 4 will operate through the link 34 to close the toe gripper and then to rock the gripper forwardly away from the sole rest, the pulling lever turning about its pivotal connection with the gripper rod 25 until the lost motion provided by the pin and slot connection between said rod and the sleeve 24 has been exhausted after which the toe gripper will be pulled downwardly. By this operating mechanism there is effected first a seizing and then a foredrawing of the upper in approximately the slant of the top face of the last, Fig. 1, unaccompanied by a downdrawing and finally a downdrawing is effected unaccompanied by further foredrawing. The length of foredraw is not arbitrarily determined by the amount of lost motion between the parts 24 and 25 but is made variable, according to the resistance of the stock, by the spring 35.

The horizontal guide member 5 carries a side gripper carrying sleeve 40 from opposite lateral sides of which, Fig. 2, extend arms to which are pivoted side gripper guides 42, said guides having upper and lower bearings in which can slide tubular gripper bars 44 upon the upper ends of which are formed or attached the inner jaws of the side grippers. The outer jaws 45 are pivoted to the inner jaws and are connected by links with side gripper operating rods 46 the lower ends of which are connected by links with stems 48 that extend through the laterally projecting arms of a sleeve 50 carried by the plunger head bar 22. Springs 52 encircle the stems 48 between said arms and the enlarged lower ends of the stems and render yielding the movement transmitted to the side grippers from the plunger. The said arms of the sleeve 50 are extended to form the handles 55 by which the operator may turn the sleeve 50 upon the bar 22 to depress one side gripper and raise the other for adjusting the upper transversely on the last. Alternatively the sole rest may be mounted to turn about an axis extending lengthwise of the machine and be provided with handles 57 corresponding to the handles 55 and by which the last may be turned about a longitudinal axis to adjust it within the upper held by the side grippers. Springs 56, which are shown as located between the lower bearing for the gripper bar 44 and a collar fastened on that bar hold the grippers up in normal position and maintain them upright until the jaws have been closed.

A screw 60, Fig. 1, for adjusting the side grippers longitudinally of the machine toward and from the toe gripper is confined

against endwise movement in the guide member 5 and is threaded through an upright rod 49 which has a forked connection with the sleeve 50 and extends therefrom through the sleeve 40 and through an elongated aperture in the guide member 5. Rotation of the screw slides the sleeves 40 and 50 and the two side grippers forwardly or backwardly.

A screw 65, Fig. 2, is confined against longitudinal movement by ears on the sleeve 40 and has right and left threaded connections with the two side gripper guides 42 for holding said guides in upright position and adjusting them together toward and from the sole rest, said guides turning during such adjustment about their vertical connections with the arms of the carrier sleeve 40.

By the described connections the side grippers are closed and then drawn downwardly to stretch the upper transversely.

There is a lost motion between the arms of the sleeve 50 and the stems 48 of the side gripper operating rods to permit the toe gripper to close and effect its foredrawing movement before the side grippers are closed. This is provided, see Fig. 2, by a collar 51 the upward position of which is limited by a pin extending through it and through the vertical slot in the stem 48. The space between the upper face of this collar and the lower face of the sleeve arms permits closing and pulling movements of the toe gripper before the side grippers seize it.

The operating connections from the plunger 4 to the toe and side grippers and the sole rest are preferably arranged to coördinate the movements of said grippers and sole rest so that the toe gripper will first seize the toe portion of the upper loosely applied to a last the toe end of which is abutted against the upturned end 15 of the sole rest. After having seized the toe end of the upper the toe gripper will move forwardly to stretch the upper lengthwise without substantially bending it over the toe end of the last, following in this respect the method of pulling uppers described in United States Letters Patent No. 855,831 dated June 4, 1907 granted on application of Emery Bayard. During the forwardly drawing movement of the toe gripper the sole rest is moved rearwardly, carrying the last with it so that the upper is stretched lengthwise by the combined movements of the sole rest and the toe gripper. Near the end of the foredrawing movement of the toe gripper the side grippers seize the upper and then move for downdrawing the upper, the toe gripper at this time moving downwardly in company with the side grippers and preferably the sole rest continuing to move rearwardly until the end of the downdrawing movement. The plunger may be locked or may be manu-

ally held with the parts in this position while the operator inspects the work and if necessary makes adjustments thereof by the use of the handles 55 or 57. Then he fastens the upper to the last by tacks inserted through the upper into the side faces of the last or at such points as he may consider desirable. When the plunger is freed the grippers and sole rest return to normal position and the grippers open for the reception of another shoe.

Fig. 3 shows a modified form of toe gripper mechanism in which the pulling lever 26 of Fig. 1 is replaced by a pulling lever 62 which is pivotally supported on the rear end of the horizontal arm of a bell crank 64 which is fulcrumed upon the guide member 5. The pulling lever 62 has on its rear edge a shoulder which is held in engagement with the pivot rod 19 carried on the guiding member 5 by the action of the spring 65 on the bell crank. In this construction the leverage exerted by the bell crank and shoulder against the rod 19 maintains the toe gripper in normal relation to the sole rest until the gripper has seized the upper after which the pulling lever 62 swings outwardly from the sole rest. This toe gripper has only upper seizing and foredrawing movements.

In the simpler form of the machine shown in Figs. 4, 5 and 6 the base which is formed to rest on a bench is made integral with the column and the plunger 70 has on its head a forwardly extending arm to which is pivotally connected a downwardly and outwardly extending link 72 the lower end of which has a pin and slot connection with the toe pulling lever 75 which is fulcrumed to the base at 74 and is turned toward the sole rest by a spring plunger 76 as far as is permitted by the adjustable stop 78 which is carried by the lever and adapted to engage a laterally fixed abutting face as shown in Fig. 4. An upper gripping lever having a jaw cooperating with the jaw formed on the upper pulling lever is pivoted to the pulling lever at 80 and has its rear end connected by a spring 82 with the pin 73, there being also a pin and slot connection between said rear end of the lever and the link 72. By this arrangement downward movement of the plunger 70 allows the spring 82 to move the gripping lever for closing the jaws and seizing the upper while the slot in the rear end portion of the link 72 permits that link to move with relation to the pin 73 on the pulling lever. When the upper end of the slot is reached the link acts against the pin 73 to turn the pulling lever in the direction for moving the toe gripper away from the sole rest thereby pulling the upper forwardly substantially as described in connection with the forward movement of the gripper shown in Fig. 1.

The column is surrounded by a sleeve 85 which rests upon a spring 86 and has laterally extended forked ears between which are secured the lower portions of the pulling levers 88 of the side grippers, the upper ends of said levers being formed as gripping jaws. The levers 90, having co-operating jaws on the upper ends, are pivoted to the pulling levers and have their lower ends connected by links 92 to a cross bar 94 which is mounted in the plunger 70 by pin and slot connection which allows a portion of the movement for actuating the toe gripper to take place before the side grippers are closed. After the side grippers are closed they are moved downwardly together by force transmitted through the plunger and the links 92 and grippers levers to the sleeve 85, the spring 86 yielding for this purpose. The side grippers are pivotally connected to the sleeve 85 at 91 and may be fixed at different distances apart by the binding screws 93.

The base of the machine pivotally supports a lever 95 which is held by a spring 90 plunger, Fig. 4, tipped toward the toe gripper and in the upper end of this lever the sole rest 14, having the upturned lip 15 as in Fig. 1, is mounted for longitudinal adjustment by a screw 96. The lever 95 has a roll standing against an inclined face on the sleeve 85 and said sleeve, when it is depressed, rocks the lever 95 to move the sole rest and the last carried thereby rearwardly in the machine.

In the described machines the shoe is supported right side up and sole face downward and there is a downdrawing movement to stretch the upper, but the invention of course covers an equivalent updrawing movement in a machine in which the shoe is supported in reversed position.

Having now described my invention, I claim as new and desire to secure by Letters Patent of the United States:

1. A pulling-over machine having, in combination, a supporting column, a plunger operating lengthwise through it, a sole rest supported by the column and constructed and arranged to sustain a shoe with its sole face down, and upper pulling grippers connected with the plunger and arranged relatively to the sole rest to seize and stretch the upper at the sides and the toe of the shoe supported on the sole rest.

2. A pulling-over machine having, in combination, a supporting column, a plunger operating through it, a sole rest supported by the column, and upper pulling grippers connected with the plunger and arranged relatively to the sole rest to seize and pull the upper at the sides and the toe of a shoe supported on the sole rest, the machine having means for imparting automatically to the toe gripper a forward movement rela-

1
tively to the last during the pulling operation.

3. A pulling-over machine having, in combination, a supporting column, a plunger operating through it, a sole rest supported by the column, grippers arranged relatively to the sole rest to seize an upper at the sides and end of a shoe supported on the rest, and operating connections through which the plunger causes the toe gripper first to seize the upper and move forwardly relatively to the last to pull the upper longitudinally and then the plunger causes the side grippers to seize the upper and join the toe gripper in further pulling the upper.

4. A pulling-over machine having, in combination, a supporting column, a sole rest supported by the column, grippers arranged relatively to the sole rest to seize an upper at the sides and end of a shoe supported on the rest, and operating mechanism through which the toe gripper is caused first to seize the upper and move forwardly relatively to the last to pull the upper longitudinally and then the side grippers are caused to seize the upper and join the toe gripper in further pulling the upper, said operating mechanism for opposed side grippers comprising an equalizing lever through which adjustment of the upper transversely of the shoe can be effected.

5. A pulling-over machine having, in combination, a supporting column, a plunger operating through it, a sole rest supported by the column, upper pulling grippers connected with the plunger and arranged relatively to the sole rest to seize and pull the upper at the sides and the toe of a shoe supported on the sole rest, and means for effecting adjustment of the side grippers together toward and from the toe gripper for sizes of shoes and also means for adjusting said side grippers together simultaneously toward or from the middle of the machine.

6. A pulling-over machine having, in combination, a supporting column, a plunger operating through it, a sole rest supported by the column, and upper pulling grippers connected with the plunger and arranged relatively to the sole rest to seize and pull the upper at the sides and the toe of a shoe supported on the sole rest, the machine having means for causing the toe gripper to move forwardly relatively to the last during the pulling operation, said sole rest having a lip extending upwardly into position to hold the last against forward displacement by the pull of the toe gripper.

7. A pulling-over machine having, in combination, a supporting column, a plunger operating through it, a sole rest supported by the column, and upper pulling grippers connected with the plunger and

arranged relatively to the sole rest to seize and pull the upper at the sides and the toe of a shoe supported on the sole rest, the toe gripper including a lever by which the jaws thereof are rocked by the plunger movement in a direction forwardly away from the toe of the last.

8. A pulling-over machine having, in combination, a supporting column, a plunger operating through it, a sole rest supported by the column, upper pulling grippers connected with the plunger and arranged relatively to the sole rest to seize and pull the upper at the sides and the toe of a shoe supported on the sole rest, the toe gripper including a lever by which the jaws thereof are rocked by the plunger movement in a direction forwardly away from the toe of the last, and means for holding the gripper from downward movement while it is being rocked and permitting such downward movement thereafter.

9. A pulling-over machine having, in combination, a supporting column, operating mechanism, a sole rest supported by the column, upper pulling grippers arranged relatively to the sole rest to seize and pull the upper at the sides and the toe of a shoe supported on the sole rest, the machine having means for causing the toe gripper to move forwardly relatively to the last during the pulling operation, said sole rest having a lip extending upwardly into position to hold the last against forward displacement by the pull of the toe gripper, and connections operating after the toe and side grippers have seized the upper and after an initial pulling movement by the toe gripper to retract said lipped sole rest and move the last rearwardly relative to all of the grippers.

10. A pulling-over machine having, in combination, a supporting column, a plunger operating through it, a sole rest supported by the column, grippers arranged relatively to the sole rest to seize an upper at opposite sides of a shoe, and connections from the plunger to operate said grippers to pull the upper and to operate the rest to move the last backwardly within the upper while the side grippers are pulling the upper.

11. A pulling-over machine having, in combination, a supporting column, operating mechanism, a sole rest supported by the column with provision for movement longitudinally of the shoe, grippers for seizing the upper, a lever connected with the rest, and operating connections to the grippers and to said lever for causing the grippers to pull the upper and the rest to retract the last within the upper while the grippers are moving to pull the upper.

12. A pulling-over machine having, in combination, a sole rest, and a gripper arranged relatively thereto to engage the up-

- per of a shoe supported on said rest, said gripper comprising a pulling lever bent at its upper end to form the upper jaw and a gripping lever pivoted thereto and forming the lower jaw, and an actuator having a yielding connection with the gripping lever and a lost motion connection with the pulling lever to cause said gripper to seize and then to pull the upper.
- 10 13. A pulling-over machine having, in combination, a sole rest, and a gripper arranged relatively thereto to engage the upper of a shoe supported on said rest, said gripper comprising a pulling lever bent at its upper end to form the upper jaw and a gripping lever pivoted thereto and forming the lower jaw, and an actuator having a yielding connection with the gripping lever and a lost motion connection with the pulling lever to cause said gripper to seize and then to pull the upper, the arrangement being such that the gripper is given an out-drawing movement after seizing the upper and then a down-drawing movement, the shoe being right side up in the machine.
- 15 14. A pulling-over machine having, in combination, a sole rest to position a shoe, and a gripper arranged to have an upper seizing, an outdrawing and then a down-drawing movement in the order stated, and comprising a pulling lever having a jaw, a gripping lever having a jaw and connected to the pulling lever to rock the pulling lever for outdrawing the upper after the upper is seized, and operating means having a connection with the pulling lever permitting that lever to remain substantially at rest vertically during the upper seizing and outdrawing and a connection with the gripping lever to effect the upper seizing and outdrawing and to allow the downdrawing movement to take place while the upper is held under outdrawn tension.
- 20 15. A pulling-over machine having, in combination, a sole rest to position a shoe and a gripper arranged to have an upper seizing, an outdrawing and then a down-drawing movement in the order stated relatively to said sole rest and comprising a substantially upright lever pivoted at its lower end and having its upper end formed as a jaw, means for holding it upraised and pressed toward the sole rest, a second lever pivoted thereto and presenting a second jaw, and operating mechanism acting through the second lever and its pivotal connection with the first lever to move the jaws outwardly away from the sole rest to outdraw the upper and then move them downwardly to downdraw the upper.
- 25 16. A pulling-over machine having, in combination, a sole rest to position a shoe, a support and a sleeve thereon having laterally projecting ears, gripper supports mounted thereon and carrying jaws on their upper ends, coöperating jaws pivoted thereon, a plunger movable from and toward the shoe bottom, and operating rods and an equalizer connecting the plunger to the coöperating jaws to seize and downdraw the upper at the sides of a shoe supported on the sole rest.
- 30 17. A pulling-over machine having, in combination, a sole rest to position a shoe, a support and a sleeve thereon having laterally projecting ears, gripper supports pivotally mounted on said sleeve for movement toward and from the sides of the shoe on said sole rest, gripper shanks yieldingly upheld in the supports and having jaws, co-operating jaws, and operating rods through which the jaws are closed and are drawn downwardly to pull the upper to the last on the sole rest.
- 35 18. A pulling-over machine having, in combination, a sole rest to position a shoe, a support and a sleeve thereon having laterally projecting ears, gripper supports pivotally mounted on said sleeve for movement toward and from the sides of the shoe on said sole rest, gripper shanks yieldingly upheld in the supports and having jaws co-operating jaws, operating rods through which the jaws are closed and are drawn downwardly to pull the upper to the last on the sole rest, means to effect movement of said rods, means to effect movement of the gripper supports transversely of the shoe on the sole rest, and means to effect relative movement of the grippers and the sole rest lengthwise of the shoe.
- 40 19. A pulling-over machine having, in combination, toe and side grippers, a sole rest, means for relatively actuating the sole rest and grippers to pull an upper, said sole rest being mounted for movement about an axis extending lengthwise of the shoe, and means by which the sole rest may be manually moved about said axis to effect adjustment of the last transversely within the upper held by the side grippers.
- 45 20. A pulling-over machine having, in combination, a sole rest, upper pulling grippers arranged relatively to the sole rest to seize and pull the upper at the sides and the toe of a shoe supported on the sole rest, operating means for the grippers, the toe gripper including a lever by which the jaws thereof are rocked by the operating means in a direction forwardly away from the toe of the last, and means for holding the toe gripper from downward movement while it is being rocked and permitting such downward movement thereafter.
- 50 21. A pulling-over machine having, in combination, a sole rest, grippers arranged relatively to the sole rest to seize an upper at opposite sides of a shoe, and connected mechanism to operate said grippers to pull the upper and to operate the rest to move

the last backwardly within the upper while the side grippers are moving to pull the upper.

22. A pulling-over machine having, in combination, a sole rest to position a shoe, and a gripper arranged to have an upper seizing, an outdrawing and then a down-drawing movement in the order stated, and comprising a pulling lever having a jaw, and a gripping lever having a jaw and connected to the pulling lever to rock the pulling lever for outdrawing the upper after the upper is seized.

23. In a pulling-over machine, the combination with grippers and operating means therefor, of a tread rest for the shoe supported at its front and rear ends by substantially parallel links for movement lengthwise of the shoe.

24. In a pulling-over machine, the combination with grippers and operating means therefor, of a tread rest carrier supported by substantially parallel links for movement lengthwise of the shoe, and a tread rest vertically adjustable at its front end relatively to the carrier.

25. In a pulling-over machine, the combination with grippers and operating means therefor, of a tread rest for the shoe supported at its front and rear ends by substantially parallel links for movement lengthwise of the shoe, and operating connections from the tread rest to the gripper operating means.

26. In a pulling-over machine, the combination with grippers and operating means therefor, of a tread rest having a member formed to engage the toe end face of the last, and connections from the gripper operating means to cause said member to move the last longitudinally while the grippers are being moved to pull the upper.

27. In a pulling-over machine, an end abutment for a last and a gripper comprising an upright pivoted at its lower end and having a jaw extending toward said abutment, a lever pivoted to said upright and having on one end a gripping face extending under said jaw, and operating means connected to the other end of said lever and adapted to effect first a gripping movement and then an upper pulling movement of the gripper about the first-mentioned pivot away from said abutment.

28. In a pulling-over machine, a sole rest, an end abutment for a last, and a gripper comprising an upright pivoted at its lower end to a vertically movable support and having a jaw extending toward said abutment, a lever pivoted to the upright and extending under said jaw, and means operating through the lever to grip the upper against the jaw, then to swing the gripper forwardly away

from the abutment and then to move the gripper and said support downwardly away 65 from the sole rest.

29. In a pulling-over machine, last resting means, a gripper, and means to close the gripper and then move it outwardly away from the last until a predetermined out-drawing force has been applied and then automatically to move the gripper in the direction to wrap the upper against the side face of the last.

30. In a pulling-over machine, last resting means, a gripper, and connected operating mechanism including a yielding element constructed and arranged to move the gripper outwardly from the last until the resistance of the upper to such movement overcomes 80 the yielding element and then automatically to move the gripper in the direction to wrap the upper against the side face of the last.

31. In a pulling-over machine, the combination with a tread rest and side grippers, of means for relatively moving the side grippers and the tread rest to stretch the upper transversely across its last, and handles projecting laterally from opposite sides of the machine within convenient reach of the operator and adapted for manipulation to move the side grippers and the tread rest relatively for adjusting the pulled upper transversely on the last.

32. In a pulling-over machine, the combination with a tread rest and side grippers, of means for relatively moving the side grippers and the tread rest to stretch the upper transversely across its last, and an arm projecting laterally from the tread rest into position to be engaged by the operator and adapted for manipulation to tip the tread rest and the last laterally within the upper held by the side grippers to effect relative transverse adjustment of the upper and the last.

33. In a pulling-over machine, the combination with a tread rest and side grippers, of means for relatively moving the side grippers and the tread rest to stretch the upper transversely across its last, an equalizer through which the pull of the opposed side grippers is made the same at the two sides of the shoe, and a handle extending laterally of the machine from the equalizer and adapted for manipulation to turn the equalizer and move the grippers in opposite directions to adjust the upper transversely on the last.

In testimony whereof I have signed my 120 name to this specification in the presence of two subscribing witnesses.

ARTHUR BATES.
